UNITED STATES PATENT OFFICE.

CHARLES SONNEBORN AND PAUL R. KAMMERER, OF BRADDOCK,
PENNSYLVANIA.

ADVERTISING APPARATUS.

SPECIFICATION forming part of Letters Patent No. 634,248, dated October 3, 1899.

Application filed February 17, 1899. Serial No. 705,854. (No model.)

To all whom it may concern:

Be it known that we, CHARLES SONNEBORN and PAUL R. KAMMERER, residents of Braddock, in the county of Allegheny and State 5 of Pennsylvania, have invented a new and useful Improvement in Advertising Apparatus; and we do hereby declare the following to be a full, clear, and exact description thereof.

Our invention relates to advertising apparatus.

The object of our invention is to provide a simple and convenient means of changing the advertising-cards in that class of advertising apparatus in which the advertising-cards are 10 rolled up on a roll and dropped therefrom in succession to be exposed to view through a suitable opening in the frame containing the roll. To these ends our invention comprises the novel features hereinafter set forth and 15 claimed.

To enable others skilled in the art to make and use our invention, we will describe the same more fully, referring to the accompanying drawings, in which—

Figure 1 is a longitudinal section of a suitable roll embodying our invention. Fig. 2 is 20 a side view of a portion of a suitable frame for carrying the roll and advertisements with side plate removed to show the construction 25 of one end of the roll.

Like letters of reference indicate like parts in each view.

In the drawings, the letter *a* designates a frame or casing of any suitable construction, 30 which is provided with the openings *b* *b'* in the front face thereof. The upper portion *a'* of the frame with the opening *b* therein is curved to conform to the roll *c*, which carries the advertising sheets or cards *m*. The roll 35 *c* has the central shaft *c'*, which connects the end plates *c²* *c³*. These end plates have the journals *c⁴*, which are mounted on suitable bearings *a²* in the frame *a*. The end plate *c³* 40 has the pulley *e*, which is connected up by a belt to a suitable motor. The end plates *c²* *c³* of the roll *c* are adapted to support the rods *i*, said rods at one of their ends fitting in 45 seats *i'* in the end plate *c³*, the opposite ends of said rods fitting in openings *i²* in the end 50 plate *c²*. Secured to the end plate *c²* is the disk *k*, which is formed of suitable spring

metal slotted radially. This provides a series of radial spring-arms *k'* in line with the openings *i²* of the end plate *c²*, one for each of said openings. By this construction the 55 rods *i* may be readily inserted and withdrawn from the roll, as by inserting the rods into the openings *i²* the arms *k'* will yield and permit of the insertion of the opposite ends in the seats *i'* of the end plate *c³*, as clearly 60 shown in Fig. 1. The rods *i* may be composed of wire of any suitable gage, great rigidity not being an essential feature of said rods.

Connected to each rod *i* is an advertising-sheet *m*, which may be formed of paper, cloth, 65 or other material which will roll up on the roll *c*. Both sides of each sheet bears an advertisement printed or otherwise applied thereto. The free ends of the sheets *m* are attached to rods *m'*, which prevent the curling up of the sheets when in their suspended 70 positions and at the same time furnish the weight required to drop the sheets after the roll has passed beyond a certain point, all of which will be more fully hereinafter set forth. 75

At about the mid-portion of the frame *a*, above the frame *c*, is the spring-arm *n*, attached to said frame at *n'*. At the outer end of said arm is the idle roller *n²*. The spring-arm *n* acts to hold the roller *n²* normally in 80 contact with the sheets *m* rolled on the roll *c*.

The advertising-sheets to be used are secured to the roll in the manner hereinbefore set forth, said sheets when rolled up on the roll overlapping each other in the manner 85 illustrated. When power is applied through the motor to rotate the roll *c*, there will always be two advertisements exposed to view through the openings *b* *b'*, that seen through the upper opening *b* being rolled on the roll 90 *c* and that seen through lower opening *b'* being suspended from said roll, as clearly shown in Fig. 2. As the roll continues to rotate in the direction indicated by the arrow, Fig. 2, the sheet exposed at the upper opening *b* will 95 move until the rod *m'* at its free end passes beyond the roller *n²*, the arm *n* yielding sufficiently to release said rod. The arm *n* prevents the sheet from falling before the proper time, and only one sheet can fall at a time. 100 Immediately the rod *m'* is released said rod will drop of its own weight, falling down

through the space r between the roll c and front of the frame. As soon as the rod m' passes beyond the space r it will swing the sheet down to a suspended position in front 5 of the opening b' . By this falling of the sheet the said sheet has been reversed and the advertisement on that side is exposed to view, while the sheet on the roll just beneath that one which has just fallen is exposed at the 10 upper opening b . The roll may be arranged to rotate at any desired rate of speed, preferably at a slow rate, in order that the advertisements will remain exposed for a sufficient length of time to permit of the viewing 15 and reading of same. After the apparatus has been once set in motion no further attention need be given to it, as the advertisements will follow each other in regular succession. The sheets may be quickly removed 20 from the roll and new ones substituted when desired, so that the advertisements may be transferred from one machine to another and a variety maintained.

What we claim as our invention, and desire 25 to secure by Letters Patent, is—
1. In advertising apparatus, a suitable

frame, a rotatable roll mounted therein, one of the ends of said roll having seats therein, the opposite end of said roll having openings therein, a spring-metal disk secured to the 30 last-mentioned end of said roll, said disk having radial slits to form spring-arms in line with said openings, and rods adapted to enter said seats and openings in said ends, substantially as set forth.

2. In advertising apparatus, a suitable frame, a rotatable roll mounted therein, one of the ends of said roll having seats therein, the opposite end of said roll having openings therein, a spring on said roll in line with each 35 of said openings, and rods adapted to enter said seats and openings, substantially as set forth.

In testimony whereof we, the said CHARLES SONNEBORN and PAUL R. KAMMERER, have 40 hereunto set our hands.

CHARLES SONNEBORN.
PAUL R. KAMMERER.
